MACHINE FOR FORMING CONTINUOUS
WIRE COILSDavid E. Crooker, Ontonagon, Mich., assignor of
one-half to Lloyd L. Felker, Marshfield, Wis.

Application January 12, 1950, Serial No. 138,225

8 Claims. (Cl. 153—64)

1

This invention relates to improvements in machines for forming continuous wire coils.

Devices which have been heretofore developed for the formation of continuous wire coils have operated on the principle of using a positive pushing action to feed the uncoiled wire stock against an angular surface. This operation was designed to impart a uniform curvature to the wire.

In certain applications, such as in the manufacture of non-skid rubber traction members, it is desirable to employ metal coils which are formed of wire which has been corrugated prior to its being made into coils. The conventional type of wire coiling devices as above referred to are unsatisfactory when handling corrugated wire due to the high incidence of failure of the wire, either during the forming operation, or soon after the coil is put to use, which failure is caused by the increase in the amount of bend which is already present in corrugated wire. This increased bend results when the corrugated wire is pushed against the angled surface of the device, the wire tending to squeeze together somewhat like an accordion, and thereby causing the corrugations which are already in the wire to be bent to a greater extent. This greatly weakens the wire. Since a relatively hard steel wire is required for the coil, its tendency toward brittleness increases the possibilities of fracture.

It is therefore a general object of the present invention to provide a wire coil forming machine which is capable of forming a continuous coil from either straight or corrugated stock without danger of seriously weakening or of fracturing the wire.

A further object of the invention is to provide a machine for forming continuous wire coils wherein the uncoiled wire is pulled into, rather than pushed into the machine, thereby eliminating the possibility of increasing the amount of bend in corrugated wire or of undesirably bending a straight wire.

A further object of the invention is to provide a machine of the class described wherein the unformed wire is formed into a coil by being pulled around and held against the periphery of a freely rotatable cylindrical mandrel, there being a plurality of driven rollers which are disposed around the periphery of said mandrel in a predetermined angular relationship therewith and which coat with the wire.

A further object of the invention is to provide a machine of the class described which can be readily adjusted to form coils of various pitch by varying the angularity of the rollers.

2

A further object of the invention is to provide a machine of the class described wherein one convolution only of the wire contacts the mandrel, thereby limiting the sliding contact of said wire with said mandrel to said one convolution, the disposition of the rollers being such as to engage the formed coil with a compressive rolling contact, and there being substantially no sliding engagement between the formed coil and said rollers.

A further object of the invention is to provide a machine of the class described wherein the rollers can be moved axially on their supporting shafts to vary the compressive forces exerted by said rollers on the coil.

A further object of the invention is to provide a machine of the class described, wherein the rollers can readily be simultaneously swung away from and toward the mandrel to permit easy access to the mandrel assembly and to said rollers.

A further object of the invention is to provide a machine of the class described which is strong and durable, efficient in operation, and otherwise well adapted for the purposes described.

With the above and other objects in view, the invention consists of the improved coil forming machine; and all of its parts and combinations, as set forth in the claims, and all equivalents thereof.

In the drawings accompanying and forming a part of this specification, wherein the same reference characters indicate the same parts in all of the views, and wherein is shown one complete embodiment of the preferred form of the invention:

Fig. 1 is a perspective side view of the improved coil forming machine taken from a point forwardly of and at one side of the machine;

Fig. 2 is a perspective side view of the machine of Fig. 1 taken from a point rearwardly of and at the same side of the machine;

Fig. 3 is a perspective front view of the machine shown in Figs. 1 and 2;

Fig. 4 is a view similar to Fig. 3, but showing the rollers moved outwardly from the mandrel and with the wire coil removed; and

Fig. 5 is a view taken approximately along the line 5—5 of Fig. 3, with two rollers removed and with a portion of the mandrel assembly broken away and shown in section.

Referring more particularly to the drawing, the numeral 10 indicates a base plate on which are fixedly mounted three vertically extending, substantially rectangular bearing plates 11, 12 and 13. The plate 11 is the smallest, and the

plates 12 and 13 are successively larger than plate 11. The plates 11, 12 and 13 are respectively formed with circular apertures 14, 15 and 16 which vary in size similarly to the plates in which they are formed. The plates are also formed with slots 17, 18 and 19 which afford communication between said apertures and the upper edges of the respective plates. The plates 11, 12 and 13 are also provided with pairs of upstanding ears 20 fixed thereto adjacent the slots 17, 18 and 19, each of said pairs of ears being provided with a tightening bolt 21.

Mounted in the circular apertures 14, 15 and 16 respectively, are circular plates 22, 23 and 24, each of which have substantially the same diameter as that of its aperture. The circular plates 22, 23 and 24 are slidable within their respective mounting apertures when the bolts 21 are in loosened condition.

The circular plate 22 is formed with substantially rectangular peripheral notches 25, 26 and 27 which are spaced apart approximately 120°. Formed in the bases of the notches 25, 26 and 27 and extending radially inwardly therefrom are substantially rectangular notches 28, 29 and 30. Mounted in the notches 28, 29 and 30 are spherical or ball and socket bearings 31, 32 and 33, through which shafts 34, 35 and 36 rotatably project. The bearings 31, 32 and 33 are held in place by suitable retaining bars 37, 38 and 39 positioned in and fixed to the bases of the notches 25, 26 and 27.

The circular plate 23 is formed with peripheral notches 40, 41 and 42 which are similar to the notches 25, 26 and 27 in the plate 22, and is formed with notches 43, 44 and 45 which are similar to the notches 28, 29 and 30 in the plate 22. Mounted in the notches 43, 44 and 45 are spherical, or ball and socket bearings 46, 47 and 48 through which the shafts 34, 35 and 36 also rotatably project. The bearings 46, 47 and 48 are held in place by retaining bars 46', 47' and 48'.

The circular plate 24 is formed with peripheral notches 49, 50 and 51 and 52, 53 and 54 which are similar to the notches 40 and 43 respectively in the plate 23. Mounted in the notches of the plate 24 are spherical or ball and socket bearings 55, 56 and 57 through which relatively short shafts 58, 59 and 60 rotatably project. The bearings 55, 56 and 57 are held in place by retaining bars 61, 62 and 63 which are fixedly mounted in the notches 49, 50 and 51.

Referring to Fig. 2, it will be noted that sprockets 64, 65 and 66 are fixed to the outer end portions of the shafts 58, 59 and 60, respectively. One of the shafts 58, 59 or 60 may be connected to a suitable source of rotative power. Figs 1 and 2 show a hand crank 67 connected to the shaft 58 for driving purposes. An endless chain 68 circumscribes and drivingly connects all of the sprockets 58, 59 and 60 as shown.

The inner ends of the short shafts 58, 59 and 60 are connected to the adjacent ends of the shafts 34, 35 and 36 by means of universal joints 69, 70 and 71. Keyed onto the opposite ends of the shafts 34, 35 and 36 are substantially cylindrical rollers 72, 73 and 74. The rollers are fixed against rotative movement relative to their shafts, but may be selectively moved axially of said shafts for a purpose to be later described. The rollers 72, 73 and 74 are provided with set screws 72', 73' and 74' respectively for releasably fixing said rollers to their shafts; the set screws. 75 22.

upon being loosened, permitting axial movement of the rollers on their shafts.

The circular plate 22 is formed with an axially extending bore 75 (see Fig. 5) through which extends that portion of a mandrel assembly 76 which is mounted on the plate 22. The assembly 76 consists of a freely rotatable, elongated cylindrical mandrel 77 having a flanged bearing sleeve 78 fixedly mounted adjacent one end thereof as by set screws 79. The flange of the collar 78 has an annular groove formed in its face and forms part of a thrust bearing which is made up of a plurality of balls 80 mounted in suitable retainers and which includes a second flanged sleeve 81, the flange of which is also formed with an annular groove. The sleeve 81 has a polygonal shoulder portion 82 and has an elongated portion 83 which is externally threaded and which projects through the bore 75. The sleeve 81 has an axial bore having a diameter substantially equal to that of the mandrel 77.

Threaded on that portion 83 of the sleeve 81 which is on the opposite side of the plate 22 from the shoulder 82 is a nut 84 which secures the sleeve 81 against axial movement. Threaded on the portion 83 of the sleeve 81 adjacent the nut 84 is a sleeve 85 which has a threaded bore 86 and which has an unthreaded bore 87, the diameter of which is substantially the same as the diameter of the mandrel 77. The sleeve 85 has two portions 88 and 89 of reduced outside diameter, as shown, and the outer end portion of said sleeve is formed with a helical end surface 90. The end surface 90 is spaced axially inwardly from the adjacent end of the mandrel 77.

Mounted on the outer face of the plate 11 adjacent the aperture 14 therein is an angle bracket 91 having a portion 92 extending toward the mandrel 77. Adjustably mounted on the portion 92 of the bracket 91 is a wire feed guide member 93. The member 93 may consist of a pair of elongated bars 94 and 95, one of which is formed with a longitudinal rectangular groove 96 in the meeting face thereof (see Figs. 1, 2 and 4). The inner ends of the bars 94 and 95 are preferably tapered as shown in Fig. 4, and said bars are secured to each other by cap screws 97, the guide member 93 being secured to the bracket 91 by cap screws 98 (see Figs. 3 and 4).

Fixed to the outer face of the circular disc 22 are a pair of spaced pins 99 which project outwardly and which are adapted to be engaged by a wrench 100, the latter being formed with cooperating holes to receive said pins. By loosening the adjustment bolt 21 on the upper edge of the plate 11, the circular plate 22 can be rotated from the position of Fig. 3 to the position of Fig. 4. As this is done, the angularity of the shafts 34, 35 and 36 is changed and the rollers 72, 73 and 74 are moved outwardly, as shown in said figures.

To put the machine into operation, the rollers are moved to the positions of Fig. 4, and a strand of wire 101 (straight or corrugated) from any suitable source, such as the reel 101' (see Fig. 2), is fed through the guide member 93. A few convolutions of coil 102 are then formed by hand winding the wire around the mandrel 77. With an extent of coil thus formed, the rollers 72, 73 and 74 are then moved into the positions shown in Fig. 3 by manipulating the wrench 100 to rotate the plate 22 in a clockwise direction, as viewed in Figs. 3 and 4. The adjustment bolt 21 is then tightened to prevent rotation of the plate 22.

Referring to Fig. 5, it will be noted that substantially one convolution only of the coil 102 is in contact with the mandrel 77. The rollers 72, 73 and 74 are positioned so that the inner peripheral edge portion of each (the edge portion nearest the plate 22) engages the periphery of the convolution of the coil 102 which encircles the mandrel and holds said convolution against the mandrel. The angularity of the rollers 72, 73 and 74 is such that the outer peripheral edge portion thereof (the edge portion farthest from the plate) are positioned closer to the axis of the mandrel 77 than the inner peripheral edge portions. This results in a squeezing of the portion of the coil outwardly of the end of the mandrel between the rollers 72, 73 and 74 and creates a gripping action when said rollers are rotated.

The shafts 34, 35 and 36 and the rollers fixed thereto are then simultaneously rotated in the direction indicated in Figs. 3 and 5 by rotating one of them in a clockwise direction, as viewed in Fig. 2, any suitable means, such as by the crank 67, being employed. This rotation of the rollers 72, 73 and 74 causes simultaneous rotation of the coil 102 due to the gripping action thereon of the outer peripheral portions of said rollers. Rotation of the coil 102 causes more wire to be drawn in and around the mandrel 77 and to be formed into additional convolutions of the coil 102. As this additional wire is drawn around the mandrel 77, the mandrel rotates in the sleeves 81 and 85.

The rollers 72, 73 and 74 are disposed around the coil 102 approximately 120° apart and at such angularity that the portions of the coil 102 which are in contact with each roller are positioned in a plane of rotation of said roller. Fig. 5 shows this relationship between the coil 102 and the roller 74 wherein the straight line A—A is aligned with the portion of one convolution of the coil 102 which is in contact with the roller 74. The line B indicates the plane of rotation of the roller 74 which intersects the point of contact of the roller 74 with the convolution designated. The roller 74 is disposed so that the line A—A is parallel with the plane of rotation B (and all other parallel planes of rotation). The same relationship holds true between the other rollers and the convolutions in engagement therewith. The angularity of the rollers permits a rolling contact of the coil 102 with said rollers and causes said coil to be drawn outwardly from the mandrel as it is formed, without causing any sliding of the coil across the faces of the rollers. The only sliding contact, other than that of the wire passing through the guide 93, is the sliding of the coil longitudinally on the short extent of the mandrel with which the one convolution of said coil is in contact.

This latter sliding contact urges the mandrel 77 axially outwardly toward the rollers, but such movement is prevented by the thrust bearing formed by the sleeves 78 and 81 and the balls 80.

The operation of forming a coil 102 in the above described manner is continuous, as contrasted with the intermittent operation of prior mandrel type coil forming machines. In addition, the operation of pulling the wire in and around the mandrel, does not tend to cause any increase in the amount of bend in a corrugated wire which is formed thereby, in contradistinction to the increased bending which results when a wire is pushed against an angled plate in forming a coil.

By mounting the shafts 34, 35 and 36 in the

manner described and shown, so that they are movable between the positions of Figs. 3 and 4, the rollers 72, 73 and 74 are capable of forming coils from wire of various diameters. By replacing the mandrel assembly 76 with an assembly in which the mandrel is of different selected diameter, coils of the new selected diameter can be formed. By changing the rollers 72, 73 and 74 for others of a different selected diameter, a still further range of coil diameter and wire thickness is made possible.

Movement of the rollers 72, 73 and 74 axially on their shafts changes the spacing between the axis of the mandrel 77 and the nearest outer peripheral edge portion of the rollers. Moving the rollers toward the plate 22 increases this spacing, and movement away from the plate decreases this spacing. The effect of such movement of the rollers is to increase or decrease the squeezing pressure of the rollers on the portion of the coil adjacent the outer peripheral edges thereof, without effecting the amount of pressure exerted on the portion of the coil encircling the mandrel 77. The adjustment of the amount of squeeze exerted by the rollers makes possible the prevention of slippage between said rollers and the coil 102.

From a comparison of Figs. 3 and 4 it is apparent that movement of the rollers outwardly by rotation of the plate 22 changes the angular relationship of said rollers. A specific angularity of the rollers causes said rollers to urge the portion of the coil in engagement therewith in a specific direction, to thereby form a coil of a specific pitch. It is apparent that a variety of coils having various diameters, pitches and wire thickness can be manufactured on the improved machine.

Various other changes and modifications may be made without departing from the spirit of the invention, and all of such changes are contemplated as may come within the scope of the claims.

What I claim is:

45. 1. In a machine for manufacturing continuous wire coils, a freely rotatable mandrel having an exposed end portion which is adapted to receive an extent of wire therearound forming one convolution of a coil; a source of supply of wire; a plurality of spaced rollers disposed adjacent said end portion of the mandrel and biased with respect thereto on convergent axes, said rollers being located so that their peripheries engage said coil convolution as well as portions of the coil beyond the end of the mandrel; and means for causing simultaneous rotation of said rollers, said rollers being so disposed with respect to said mandrel and coil that when said rollers are rotated the coil and mandrel are rotated to draw wire around the mandrel from said source of supply and to deliver coiled wire longitudinally off of the mandrel end portion, the axially convergent disposition of said rollers being such that the peripheral portions of said rollers which are in engagement with portions of the coil beyond the end of the mandrel are positioned closer to the mandrel axis than the portions engaging the coil convolution on the mandrel, to thereby provide a gripping action on the portion of the coil beyond the end of the mandrel.
50. 2. In a machine for manufacturing continuous wire coils, a freely rotatable mandrel having an exposed end portion which is adapted to have an extent of wire wound therearound to form one convolution of a coil; a source of supply of

wire; a plurality of spaced substantially cylindrical rollers disposed adjacent said end portion of the mandrel and biased with respect thereto, said rollers being located so that a portion of each of their peripheries engages said coil convolution and so that another peripheral surface portion of each roller extends beyond the end of the mandrel; and means for causing simultaneous rotation of said rollers, said rollers being so disposed with respect to said mandrel and coil that when said rollers are rotated the coil and mandrel are rotated to draw wire around the mandrel from said source of supply and to deliver coiled wire longitudinally off of the mandrel end portion, the rollers being disposed with a peripheral surface portion beyond the end of the mandrel positioned closer to the mandrel axis than the peripheral surface portion thereof in engagement with the coil convolution on the mandrel, thereby creating a gripping action of said rollers on the portion of the coil beyond the end of the mandrel.

3. In a machine for manufacturing continuous coils, a freely rotatable mandrel having an exposed end portion which is adapted to receive an extent of wire therearound forming one convolution of a coil; a source of supply of wire; a plurality of spaced rollers positioned adjacent said end portion of the mandrel with their axes convergent and located so that their peripheries engage said coil convolution as well as portions of the coil beyond the end of said mandrel, said rollers being biased with respect to said mandrel such that the portion of the convolution engaged by a roller extends in a direction substantially parallel to a plane of rotation of said roller; and means for causing simultaneous rotation of said rollers to rotate said coil and mandrel and draw wire around the mandrel from said source of supply and deliver coiled wire longitudinally off of the mandrel end portion, the convergent axial disposition of said rollers being such that the peripheral portions of said rollers in engagement with the portions of the coil beyond the end of the mandrel are positioned closer to the mandrel axis than the portions engaging the coil convolution on the mandrel, to thereby provide a gripping action on the portion of the coil beyond the end of the mandrel.

4. In a machine for manufacturing continuous coils, a freely rotatable mandrel having an exposed end portion which is adapted to have an extent of wire wound therearound to form one convolution of a coil; a source of supply of wire; a plurality of spaced cylindrical rollers positioned adjacent said end portion of the mandrel and located so that a portion of the periphery of each engages said coil convolution and so that another portion of the periphery of each roller extends beyond the end of the mandrel, said rollers being so biased with respect to said mandrel that the portion of the convolution engaged by a roller extends in a direction substantially parallel to a plane of rotation of said roller; and means for causing simultaneous rotation of said rollers to rotate said coil and mandrel to draw wire around the mandrel from said source of supply and to deliver coiled wire longitudinally off of the mandrel end portion, the rollers being disposed with the peripheral surface portions thereof which are beyond the end of the mandrel positioned closer to the mandrel axis than the peripheral surface portions thereof which are in contact with the convolution on the mandrel, thereby creating a

gripping action on the portion of the coil beyond the end of the mandrel.

5. In a machine for manufacturing continuous wire coils, a freely rotatable mandrel having an exposed end portion which is adapted to receive an extent of wire therearound forming one convolution of a coil; a source of supply of wire; a plurality of spaced substantially cylindrical rollers disposed adjacent said end portion of the mandrel and biased with respect thereto, said rollers being located so that a portion of the periphery of each engages said coil convolution and so that another portion of the periphery of each roller extends beyond the end of the mandrel; a rotatable supporting shaft for each of said rollers, said rollers being mounted on said shafts in a manner to prevent relative rotative movement thereon and to permit selective adjustment of their axial positions thereon; and means for causing simultaneous rotation of said rollers, said rollers being so disposed with respect to said mandrel and coil that when said rollers are rotated the coil and mandrel are rotated to draw wire around the mandrel from said source of supply and to deliver coiled wire longitudinally off of the mandrel end portion, the rollers being disposed with the peripheral surface portions thereof which are beyond the end of the mandrel positioned closer to the mandrel axis than the peripheral surface portions thereof which are in engagement with the coil convolution on the mandrel, thereby creating a gripping action of said rollers on the portion of the coil beyond the end of the mandrel, said gripping action being selectively controlled by adjustment of the axial positions of said rollers on their supporting shafts.
6. In a machine for manufacturing continuous wire coils, a freely rotatable mandrel having an exposed end portion which is adapted to receive an extent of wire therearound forming one convolution of a coil; a source of supply of wire; a plurality of spaced substantially cylindrical rollers disposed adjacent said end portion of the mandrel, said rollers being located so that a portion of the periphery of each engages said coil convolution and so that another portion of the periphery of each roller extends beyond the end of the mandrel; a rotatable supporting shaft for each of said rollers, said rollers being mounted on said shafts in a manner to prevent relative rotative movement thereon and to permit selective adjustment of their axial positions thereon, said rollers being so biased with respect to said mandrel that the portion of the convolution engaged by a roller extends in a direction substantially parallel to a plane of rotation of said roller; and means for causing simultaneous rotation of said rollers, to rotate said coil and mandrel to draw wire around the mandrel from said source of supply and to deliver coiled wire longitudinally off of the mandrel end portion, the rollers being disposed with the peripheral surface portions thereof which are beyond the end of the mandrel positioned closer to the mandrel axis than the peripheral surface portions thereof which are in engagement with the coil convolution on the mandrel, thereby creating a gripping action of said rollers on the portion of the coil beyond the end of the mandrel, said gripping action being selectively controlled by adjustment of the axial positions of said rollers on their supporting shafts.
7. In a machine for manufacturing continuous wire coils, a mandrel having an exposed end portion which is adapted to have an extent of wire wound therearound to form one convolution

of a coil; a source of supply of wire; a plurality of spaced rollers disposed adjacent said end portion of the mandrel and biased with respect thereto, said rollers being located so that a portion of each of their peripheries engages said coil convolution and so that another peripheral surface portion of each roller extends beyond the end of the mandrel; and means for causing simultaneous rotation of said rollers, said rollers being so disposed with respect to said mandrel and coil that when said rollers are rotated the coil is rotated to draw wire around the mandrel from said source of supply and to deliver coiled wire longitudinally off of the mandrel end portion, the rollers being disposed with a peripheral surface portion beyond the end of the mandrel positioned closer to the mandrel axis than the peripheral surface portion thereof in engagement with the coil convolution on the mandrel, thereby creating a gripping action of said rollers on the portion of the coil beyond the end of the mandrel.

8. In a machine for manufacturing continuous wire coils, a mandrel having an exposed end portion which is adapted to receive an extent of wire forming one convolution of a coil; a source of supply of wire; a plurality of spaced rollers disposed adjacent said end portion of the mandrel and biased with respect thereto on convergent axes, said rollers being located so that their peripheries engage said coil convolution as well as portions of the coil beyond the end of the mandrel; and means for causing simultaneous rotation of said rollers, said rollers being so disposed with respect to said mandrel and coil that when said rollers are rotated the coil and man-

drel are rotated to draw wire around the mandrel from the source of supply and deliver coiled wire longitudinally off of the mandrel end portion, the axially convergent disposition of said rollers being such that the peripheral portions of the rollers which are in engagement with portions of the coil beyond the end of the mandrel are positioned closer to the mandrel axis than those portions of the rollers which engage the convolution which is still on the mandrel.
